Inventor;

UNITED STATES PATENT OFFICE.

HARRIET SWALLIE, OF SIDNEY, OHIO.

WAIST-FORM.

1,066,551.

Specification of Letters Patent.

Patented July 8, 1913.

Application filed June 17, 1911. Serial No. 633,872.

To all whom it may concern:

Be it known that I, HARRIET SWALLIE, a citizen of the United States, residing at Sidney, in the county of Shelby and State 5 of Ohio, have invented a new and useful Waist-Form, of which the following is a specification.

This invention relates to inflatable waist forms.

10 The object of the invention is to provide a novel and thoroughly practical article of this character, adapted more particularly for use by dressmakers, in the use of which accurate fitting of waists will be assured 15 irrespective of the peculiarities in the figures of different customers, and which may be employed for the purpose designed with persons of any size within reasonable bounds.

With the above and other objects in view, 20 as will appear as the nature of the invention is better understood, the same consists in the novel construction and combination of parts of an inflatable waist form, as will be hereinafter fully described and claimed.

25 In the accompanying drawing forming a part of this specification and in which like characters of reference indicate corresponding parts Figure 1 is a view in side elevation of a waist form constructed in accordance with the present invention. Fig. 2 is a view in front elevation. Fig. 3 is a horizontal sectional view taken on the line 3—3 of Fig. 2. Fig. 4 is a vertical transverse sectional view taken on the line 4—4 of Fig. 1.

30 The form embodies an inflatable bag or casing consisting of two side sections 1 and 2 that are connected at their upper and lower ends by a common neck 4 and a bottom 3, respectively, but are separated 35 throughout the remainder of their length. These sections are made of soft and easily distended rubber, preferably of the style that is employed in the manufacture of the inner tubes of bicycle tires. The neck 4 is 40

45 provided with an upstanding teat 5 to which is secured a valved filling nipple 6 of the ordinary type employed on bicycle tires and with which is designed to be connected a pump for forcing air into the two sections 50 and thus inflating them.

The stock of the inner casing will have the general outline of the waist and bust of a female, the desired contour being imparted to it by means of what is termed a "form definer" 7 which is constructed from non-elastic fabric, and is of jacket form but 55

sleeveless, and is divided along its median line at the front from end to end. A series of independent lacings 10 are threaded through the back of the definer and pass 60 between the two sections of the inflatable casing, the ends of the various lacings passing through apertures 9 in the front of the definer along the respective edges 8 formed by the division, ends of the lacings being 65 designed to be knotted or tied together.

The form in common use, is designed to rest upon a stand, the post of which is designated P, the legs L and the top T, and secured around the edges of the top is a series 70 of pins or studs S that are designed to be engaged by eyelets 12 formed in a length of tape or the like 13 secured around the lower edge of the form and extending sufficiently below the same to permit ready connection between the eyelets and the studs. In order to secure these results, with the present invention, the measurements of the waist and bust of the prospective wearer are taken, and the inner casing is inflated 75 to the desired degree, whereupon by manipulating the lacings 10, the distended form may be made to correspond to the measurements obtained, and further, by the employment of the distendable sections 1 and 2, the 80 back and front portion of the definer, are caused to maintain a relatively flat condition, corresponding to the general shape 85 of the human form.

In the event that the waist to be made is 90 for a small person, the distension of the inner casing, as will be obvious, will be less than where the waist is to be fitted to a large person, and by the employment of the lacings, one definer may be used for almost any 95 person of ordinary size. As will be obvious, with persons of very large size a larger casing or form will be required, and consequently a larger definer, but it has been found that one of the elastic forms and one 100 of the definers will be all that an ordinary dressmaker will require. After the adjustment of the definer has been completed and the form as a whole has assumed the desired shape, the lining of the waist is then cut 105 and fitted to the form, and then basted, and finally sewed in the usual manner. In addition to providing for the proper fitting of the lining, the structure hereinbefore shown may also be employed for fitting the 110 fabric of the waist, which may be accomplished by positioning the lining upon the

form and then making the material of the waist proper to fit the form with exactness.

It will be noted that the two sections of the inflatable casing or form distender being spaced apart throughout their entire length are permitted to move to and from each other so as to adjust the width of the various portions of the form, the casing in being inflated tending to spread the sections 5 apart, so that the sections may be pressed together in order to decrease the width of the various portions of the form. Thus, by tightening the various lacings, the inflatable casing may be contracted, the edges 8 being 10 drawn together so as to bring the sections of the casing closer together in order to decrease the width of the various portions of the form, and by loosening the various lacings, the sections of the inflatable casing 15 may be permitted to separate so as to increase the width of the various portions of the form. The sections of the casing in being separated also permit the front and rear of the form to be drawn together, the space 20 between the sections of the casing permitting the sections to be flattened slightly. It will therefore be possible to adjust the form without inflating or deflating the casing, and a further feature of the present invention 25 is provided by the provision of the inflatable casing constructed in two sections as defined. This feature resides in the fact, 30

that when the sections of the casing are pressed together, the shoulders of the form may be drooped or sloped as desired. 35

The improvements herein defined, while simple in character, will be found thoroughly effective for the purpose designed, and will coact in the production of a form that will be at once simple, compact, durable and effective. 40

What I claim is:

A waist form comprising a stand, a form definer detachably engaged at its lower end to the stand and divided at the front along its median line, an inflatable casing within the definer and comprising two sections spaced apart along the median line of the definer and united at their lower and upper ends by a common bottom and neck, respectively, and a series of independent lacings threaded through the back of the definer and passing between the sections of the casing, the ends of the various lacings passing through the front of the definer along the edges formed by the division and being designed to be knotted together. 45 50 55

In testimony that I claim the foregoing as my own, I have hereto affixed my signature in the presence of two witnesses.

HARRIET SWALLIE.
